J. C. FAWCETT.
PENHOLDER RECEPTACLE
APPLICATION FILED MAY 26, 1917.

1,268,224.

Patented June 4, 1918.

UNITED STATES PATENT OFFICE.

JOSEPH C. FAWCETT, OF BEN LOMOND, ARKANSAS.

PENHOLDER-RECEPTACLE.

1,268,224.

Specification of Letters Patent. Patented June 4, 1918.

Application filed May 26, 1917. Serial No. 171,146.

To all whom it may concern:

Be it known that I, JOSEPH C. FAWCETT, a citizen of the United States of America, residing at Ben Lomond, in the county of 5 Sevier and State of Arkansas, have invented certain new and useful Improvements in Penholder-Receptacles, of which the following is a specification, reference being had therein to the accompanying drawing.

10 This invention relates to a pen holder receptacle, and has for its object the production of a pocket holder, arranged so as to contain a pen holder, pen points and ink well.

15 Another object of this invention is the production of a pen holder receptacle of such a construction as to conform very easily to the shape of a pocket.

Another object of this invention is the 20 production of a pen holder receptacle, which is provided with simple and efficient means for holding the ink well and reservoir tube thereof against displacement.

A still further object of this invention is the 25 production of a pen holder receptacle, which is provided with a spring clip mounted therein, arranged so as to retain the pen holder in a fixed position, and at the same time releasably retain the ink well and 30 the reservoir thereof in a set position.

With these and other objects in view this invention consists of certain novel combinations and arrangements of parts as will be hereinafter fully described and claimed.

35 In the accompanying drawings:—

Figure 1 is a top view of the pen holder receptacle, showing the same in an open condition.

Fig. 2 is a small longitudinal section 40 through the pen holder receptacle.

Fig. 3 is an enlarged transverse section through the device taken on the line 3—3 of Fig. 2.

Fig. 4 is an enlarged longitudinal section 45 through a portion of the pen holder receptacle, taken on the line 4—4 of Fig. 3.

Fig. 5 is a transverse section of the pen holder receptacle taken on the line 5—5 of Fig. 2.

50 Fig. 6 is an elevation of one end of the device.

Referring to the accompanying drawing by numerals, will be seen a pen holder receptacle comprising a casing, having a cover 55 2 hinged secured thereto, as shown at 3.

The casing and cover have rounded outer peripheries as shown in Figs. 3 and 6, so as to constitute a comparatively rounded outer surface for eliminating uneven wearing surfaces. As a consequence the receptacle may be placed within the pocket of a garment, and owing to its rounded construction will be prevented from wearing or injuring the pocket. The coil spring 4 has its ends anchored as shown at 5 to the 60 casing 1 to the top 2, so as to releasably hold the cover in a closed or open position after the cover has been moved past a dead center. It is, of course, obvious that any other form of spring may be employed for holding the cover in either a closed or open 65 position. The casing 1 and cover 2 have end walls 6 which abut against each other, when the covers are in a closed position, as shown in Fig. 6 and as a consequence, the 70 end portions of the receptacle will be closed when the cover is fitting over the outer portions of the casing.

The partition 7 which has a rounded top 75 periphery is fixedly mounted within the casing 1, adjacent one end thereof, as shown in Figs. 1 and 2, so as to form a pocket 8 in which pen points may be carried. This partition 7 projects above the upper portions of the casing 1, so as to engage the 80 surface of the cover 2, when the cover is closed as shown in Fig. 2. As a consequence, it is obvious that the pen points will be retained within the pocket 8, and will be prevented from spilling around within the 85 receptacle, when the receptacle is carried within the pocket of a garment.

The ink-well 9 is provided with a cork 10, which of course, is intended to close the top of the ink-well when the same is not in 90 use. The elongated reservoir tube 11 has an upwardly extending portion 12 communicating with the well 9 as shown in Fig. 4. This reservoir tube 11 fits within the depressed groove 13 formed in the inner 100 portions of the casing 1, as shown in Figs. 3 and 4, and when the ink well 9 is filled it is obvious that the reservoir tube 11 will also be filled, so as to constitute a supply for the ink well.

The spring retaining clip is formed from a strip of resilient metal, comprising a loop 14 having arms 15 extending therefrom, one arm 15 terminates in a foot 16 which bears upon the casing 1, and is riveted there- 110

to, as indicated at 17. A finger 18 extends from the remaining arm 15, and this arm 15 is riveted, as shown at 17' of the casing. The finger 18, however, is placed upon the 5 casing so as to releasably fit upon the reservoir 11, for holding this tube within the depressed groove 13. As a consequence, it will be noted that the reservoir tube will be held against accidental displacement and 10 will, therefore, hold the ink well 9 in a set position within the casing. When so desired the finger 18 may be sprung outwardly so as to release the reservoir tube, if it is desired to clean or refill the ink well or the 15 reservoir tube.

It will be noted by referring particularly to Fig. 3, that the loop 14 is carried adjacent the center of the casing, and therefore is adapted to engage the pen holder 19.

20 When this pen holder receptacle is in use the cork 10 of the ink well 9 is first removed, thereby permitting access to the interior of the ink-well. As hereinbefore stated the reservoir tube 11 will also be filled so as to 25 provide an extra supply of ink for the ink well 9. After this action has taken place the cork 10, may be replaced upon the ink well 9. The pen points are positioned within the pocket 8, and the pen holder positioned 30 within the casing, so as to be held against accidental movement by means of the loop 14 of the spring clip. As a consequence since the spring clip will hold the pen holder and the ink well, and reservoir arm against 35 movement, these elements may be prevented from injuring each other by abutment within the casing. At this time the cover may be moved within a closed position, and the receptacle may be placed within the pocket 40 of a garment. When it is desired to use the pen, the cover may be moved to an open position, so as to allow the pen holder to be moved from engagement with the spring clip. The cork 10 may then be removed 45 from engagement with the ink well, and the contents of the receptacle will then be in condition for convenient use.

In the foregoing description it will be seen that a very simple pen holder receptacle has been constructed, which is provided with means for holding the pen holder, the ink well, and pen points in set 50 positions, and which is constructed so as to conveniently fit within the pocket of a garment, whereby the spring clip, and the elements positioned within the casing will be held in set positions. It is, of course, not intended to limit the construction of 55 this invention to the specific form as herein shown, for it is intended to include all such forms of the invention as properly come

within the scope of the construction as claimed.

What is claimed is:—

1. In a pen holder receptacle of the class 65 described, the combination of a casing, a cover hingedly mounted thereon, said casing having a depressed groove formed therein, an ink well having a reservoir tube extending therefrom, said reservoir tube fitting within said groove, and means for holding said tube within said groove, whereby said ink well will be held in a set position, and said means also holding a pen holder in a set position within said casing. 70

2. In a pen holder receptacle of the class described, the combination of a casing, a cover hingedly mounted upon said casing, an ink-well positioned within said casing, a reservoir tube extending from said ink-well, a spring clip positioned within said casing, said clip being formed from a single strip of resilient material, and comprising a loop, arms extending from said loop, one of said arms terminating in a foot, said 80 foot and remaining arm fixedly engaging said casing, a finger extending from said last mentioned arm, and bearing upon said reservoir tube, whereby said tube and ink well will be held in set positions, and said 85 loop also releasably retaining a pen holder. 90

3. In a pen holder receptacle of the class described, the combination of a casing, a cover hingedly mounted upon said casing, said casing having a depressed groove 95 formed therein, an ink well positioned within said casing, a reservoir tube connected to said ink well and extending therefrom, said reservoir tube fitting within said groove, a spring clip formed from a single 100 strip of resilient material, and comprising a loop, arms projecting from said loop, one of said arms terminating in a foot, means for fixedly mounting said foot, and the remaining arm upon said casing, a finger extending from the last mentioned arm, said finger fitting upon said reservoir tube, whereby said tube and ink well will be held in set positions within said casing and said 105 loop being adapted to hold a pen holder. 110

4. In a pen-holder receptacle of the class described, the combination of a casing having a depressed groove, an ink-well having a reservoir tube projecting therefrom, said tube fitting within said groove, and a resilient strip carried by said casing and bearing upon said tube, whereby said groove and strip will releasably hold said ink-well and tube in a set position within said casing. 115

In testimony whereof I hereunto affix my 120 signature.

JOSEPH C. FAWCETT.
